UNITED STATES PATENT OFFICE.

LOUIS L. TIFFANY, OF ROSLINDALE, MASSACHUSETTS, ASSIGNOR OF ONE-HALF TO
TIMOTHY McGOLDRICK, OF LINCOLN, NEW HAMPSHIRE.

INCORRECT-POSITION INDICATOR FOR PIANOS.

1,343,595.

Specification of Letters Patent. Patented June 15, 1920.

Application filed February 21, 1920. Serial No. 360,366.

To all whom it may concern:

Be it known that I, LOUIS L. TIFFANY, a citizen of the United States, residing at Roslindale, in the county of Suffolk and State of Massachusetts, have invented certain new and useful Improvements in Incorrect-Position Indicators for Pianos, of which the following is a specification, reference being had to the accompanying drawings.

This invention relates to means for indicating to a player when the arm and wrist of the player are in incorrect position.

With beginners on the piano, the wrist is weak and will naturally drop down on the keyboard, and should the pupil be allowed to do this for a while without correction, then in a very short time the wrist will form this habit of dropping down, and it is very difficult to train the pupil to bring the wrist back to the right position again, and the pupil will never be able to execute any difficult piano passage. The prospects of many pupils have been entirely ruined by the formation of this habit.

The object of my invention is to provide a device which will tend to prevent the acquirement of this habit by causing the sounding of a signal whenever the pupil allows the wrists to drop downward lower than the correct position.

A further object is to provide a device of this character which includes a longitudinally extending member operatively connected to a signal, which member, when depressed by the depression of the wrist beyond a predetermined point, will actuate the signal, thus warning the pupil of his error.

A further object is to provide a device of this character by which an electrically actuated signal may be energized, this signal being either visual, audible, or both.

And another object is to provide a device of this character which may be readily attached to any piano without being particularly obtrusive when turned out of the way, and which may be swung from an operative to an inoperative position.

Other objects will appear in the course of the following description.

My invention is illustrated in the accompanying drawings, wherein:

Figure 1 is a front elevation of a piano

having a signaling attachment thereon constructed in accordance with my invention;

Fig. 2 is a side elevation of the piano shown in Fig. 1;

Fig. 3 is a fragmentary vertical section through the keyboard of the piano showing my attachment in elevation;

Fig. 4 is a front elevation of the part shown in Fig. 3, the members 17 and 18 being partly in section;

Fig. 5 is a perspective view of the pivotal end of one of the arms 12;

Fig. 6 is a perspective view of one of the knuckles 11 coacting with the arm shown in Fig. 5;

Fig. 7 is a perspective view of the spring which urges the knuckle and corresponding arm into engagement with each other;

Fig. 8 is a fragmentary elevation of the front of the piano showing a different manner of arranging the signal.

Referring to these drawings, it will be seen that my attachment comprises the oppositely disposed brackets 10, which are intended to be disposed beneath the keyboard of a piano and out of the way, and which are provided with lugs 11 constituting knuckles. These lugs 11 extend at right angles to the plane of the brackets 10 and are disposed, therefore, in vertical planes at right angles to the front of the piano.

Pivotaly connected to these lugs are the angular arms 12, each of these arms being of relatively thin but strong metal or other suitable material, and each arm is perforated, as is the knuckle 11, for the passage of a bolt, rivet or like pivoting device 13.

The space between the heads of the rivet 13 is wider than the thickness of the knuckle 11 and of the arm 12, so that there is lateral play between the arm and the knuckle, but each arm is pressed resiliently or yieldingly against the corresponding knuckle by means of a dished spring or resilient washer 14 disposed between the inner head of the rivet or other pivotal member and the face of the knuckle.

Each knuckle is formed at nearly diametrical points with openings 15, and the corresponding arm is formed with a resilient tongue 16 constituting a pawl which is adapted to engage in either one of these recesses or perforations 15. Thus, when the arms are turned to the position shown in

full lines in Fig. 2, the pawls 16 will engage in one pair of the perforations 15 to hold the arms in their upwardly disposed position, while when the arms are swung 5 down to the dotted line position, the tongues or pawls will engage in the other set of perforations and the device will be held in its lowered position.

The upwardly extending portion 17 of 10 each arm 12 is longitudinally slotted, as at 18, and engaging against the flat face of this upwardly extending portion 17 is a flat extension 19 which may carry a bolt and wing nut 20 entering the slot in the portion 17 15 and permitting the extension 19 to be adjusted vertically. It will be understood that both the members 19 and 17 may be slotted, or only one of them may be slotted, and the nut and bolt 20 might be carried on 20 either one of these parts. The upwardly extending portion 17 of one of the brackets 12 may be formed to provide oppositely disposed clamping jaws 21, resilient in character, and adapted to support a small dry 25 battery 22 and flash lamp of the usual type, the light in this lamp being projected through the lens 23.

Supported by the upper ends of the members 19 are two approximately parallel, 30 transversely extending coiled springs or like elements 24 and 24^a, these elements being electrically conductive, and at their ends passing through the members 19 but being insulated therefrom, as by the insulating 35 strips 25. Wires 26 and 27 lead from these springs 24 to the battery 22 and the opposite ends of the springs 24 are to be connected in circuit with each other. Normally the circuit through the battery is broken by 40 the separation of the springs 24 from each other, but when the upper spring or transverse member 24 is depressed against the lower spring or transverse member 24^a, the circuit will be completed through the dry 45 battery 22 and as a consequence the lamp within the flash light will be energized and this flashing of the lamp will indicate to the player that the wrists or forearms have been depressed too much.

50 Of course, it is to be understood that the member 19 is to be adjusted properly to such a height that the uppermost spring 24 will be so disposed as to touch the forearms or wrists of the player when the arm is depressed unduly, but that the wrist or forearm will not touch or depress this member 24 unless the forearm is depressed unduly.

While I have illustrated in Fig. 3 a small 60 flash light carried as a unit with a dry battery, I do not wish to be limited to this, as the flash light (as shown in Fig. 8) might be mounted in any other desired position and connected by wires to a battery, or, as illustrated in Fig. 1, the two springs 24 and 24^a 65 might be connected at one end in circuit

with an electrically actuated signal bell 28, or other audible signal, in turn connected in circuit with one or two battery cells 29 and with the other spring, and as illustrated in Fig. 1, the flash light 22 may be disposed 70 at one end of the piano and the signal bell at the other end of the piano so that both an audible and a visual signal will be given, the audible signal being sufficient for the teacher, who may be engaged in other work, 75 while the visual signal will be sufficient for the pupil. A constant repetition of the audible signal would warn the teacher that the pupil was having trouble, which would not be obvious to the teacher necessarily 80 from the flashing of the light, or the bell might be mounted in another room from that in which the pupil was practising.

I do not wish to be limited to the use of any particular kind of signal, nor to the use 85 in combination of a visual or an audible signal, nor do I wish to be limited to the details of construction and arrangement of parts which I have specifically illustrated, as it is obvious that many changes might be 90 made within the scope of the appended claims without departing from the spirit of the invention.

The operation of the device will be obvious from what has gone before. When it is 95 desired to use the device, the arms 12 are turned up to the position shown in full lines in Fig. 2, the supporting member 19 being so adjusted as to properly position the uppermost element 24 with relation to the 100 keys of the piano. Now, as before stated, if the pupil depresses the forearm or wrist to too great an extent, the spring wire 24 will be expanded and depressed and will come in contact with the wire 24^a or other contact, and as a consequence an electric circuit will be completed through the signal of whatever kind is used, thus warning the pupil, and, if necessary, warning the teacher of the error. Immediately upon the lifting 110 of the pupil's wrists to the proper position, this circuit will be broken and the signal will cease. When it is not desired to use this "tell-tale", it may be readily disposed beneath the piano by simply forcing the 115 arms laterally against the action of the dish-shaped spring 14, and the arms may then be rotated until the latching pawls 16 engage in the lowermost notches, when the parts will be supported in the position 120 shown in dotted lines in Fig. 2, thus placing the device entirely out of the way and permitting the use of the piano in the ordinary manner.

It will be obvious that the springs 24 and 125 24^a may be made of very light wire and that the whole device may be made relatively light, as there is but very little strain on the various parts.

It will also be obvious that the springs 130

24 and 24^a, inasmuch as they urge the arm 19 toward the knuckle 11, act to hold the knuckles and the arms in engagement with each other, in other words, to some extent 5 take the place of the dished spring 14. Hence I do not wish to be limited to the use of this dished spring.

While I have heretofore referred to the fact that this device is intended to be used 10 with a piano, it will be understood that it also might be used for an organ or with any other keyed musical instrument of like character.

I claim:—

15 1. A signaling device of the character described for pianos comprising a plurality of arms attachable to the under side of the keyboard of a piano, the arms having upwardly extending portions normally disposed in front of the keyboard, electrically conductive elements carried by said arms and extending across the front of the keyboard slightly above the keys and normally out of engagement with each other but adapted to be moved into contact with each other by the depression of a player's wrists, and a signal actuated by engagement of said elements with each other upon said depression.

20 2. A signaling device of the character described for pianos including a pair of electrically conductive elements mounted across the front of a piano in front of the keys thereof, one of said elements being slightly above the keys, said elements being normally out of electrical engagement with each other, and an electrical signal and source of energy in circuit with said elements, a depression of the wrists of the player causing said elements to move into 25 contact with each other and close the circuit through said signal.

25 3. An attachment of the character described comprising brackets adapted to be attached to the under side of a piano keyboard, angular arms pivoted to said brackets for movement into a depressed position or a raised position, said arms having angular portions adapted, when the arms are raised, to extend vertically upward in front 30 of the keyboard, electrically conductive, elastic elements carried by said arms and extending between said arms and normally out of contact with each other and a source of energy, and a signal electrically connected to said elements whereby when said elements are forced into contact with each other a circuit will be closed through the signal and source of energy.

35 4. A signaling device of the character described for pianos comprising brackets adapted to be attached to the under side of the keyboard of a piano and having knuckles, angular arms loosely pivoted to the knuckles, springs forcing the arms 40 against the knuckles, each arm and corre-

sponding knuckle having, one a plurality of recesses and the other a resilient pawl adapted to engage in said recesses to latch the arms in their raised or lowered positions, coiled contractile springs of conductive material carried by the said arms and extending transversely across the piano slightly above the keys thereof, and an electrically actuated signal connected in a circuit with a source of energy and said 70 springs, whereby when said springs are forced into engagement with each other a circuit will be completed through the signal.

5. A signaling device of the character described for pianos comprising a pair of brackets adapted to be mounted beneath the keyboard of the piano and having perforated knuckles, angular arms engaging said knuckles, pivot members passing through the knuckles and arms and engaging them with each other, means for holding the arms in a raised or depressed position on the knuckles, a member adjustable on the angular extremity of each arm, a pair of coiled springs carried by and insulated from said 80 members and extending transversely between the arms, the springs being normally separated from each other and being of conductive material and under tension, and a signaling device connected in circuit with a 85 source of current and said springs.

6. A signaling device of the character described for pianos comprising a pair of brackets adapted to be mounted beneath the keyboard of the piano and having perforated knuckles, angular arms engaging said knuckles, pivot members passing through the knuckles and arms and engaging them with each other, means for holding the arms in a raised or depressed position on the 90 knuckles, one of said arms being formed with a receptacle, a battery and signal carried by said receptacle, transversely extending, coiled contractile springs operatively carried by but insulated from said arms and 95 extending transversely between the arms and connected in a normally open circuit with said battery and signal, whereby when one of said springs is forced into engagement with the other a circuit will be completed between the battery and signal.

7. The combination with a piano having a keyboard, of means for indicating the correct position of the wrists of a player comprising members extending horizontally 100 across the piano in spaced relation to each other, one of said members being disposed slightly above the keyboard, said members being adapted to be forced into engagement with each other by an undue depression of 105 the wrists of a player, and a signal operatively connected to said members and actuated by a shifting of the members into engagement with each other.

8. The combination with a piano having 110

4
a keyboard, of a member extending transversely of the piano slightly above the keyboard, a signal, and means actuated by a depression of said member causing the operation of the signal.

9. The combination with a piano, of supporting members adjustably mounted upon the piano for movement into or out of operative position, yieldable, transverse members carried by the said supporting members

and normally disposed slightly above the keyboard of the piano and in front thereof, and a signal operatively connected to said yieldable members and adapted to be actuated when the members are forced into engagement with each other by the undue vibration of the wrists of a player. 15

In testimony whereof I hereunto affix my signature.

LOUIS L. TIFFANY.
